UNITED STATES PATENT OFFICE.

ARTHUR A. KELLEY, OF SPOKANE, WASHINGTON, ASSIGNEE OF ONE-HALF TO JAMES K. HIGGINS, OF SPOKANE, WASHINGTON.

DETONATING DOOR-FASTENING DEVICE.

1,403,502.

Specification of Letters Patent. Patented Jan. 17, 1922.

Application filed January 15, 1921. Serial No. 437,556.

To all whom it may concern:

Be it known that I, ARTHUR A. KELLEY, a citizen of the Dominion of Canada, residing at Spokane, in Spokane County and State 5 of Washington, have invented certain new and useful Improvements in Detonating Door-Fastening Devices, of which the following is a specification.

My present invention relates to an improved detonating door fastening of the portable type, adapted as a burglar alarm for use in fastening a closed door or window, for the combined functions of securing the door or window, and providing an alarm in 10 case of burglary or surreptitious opening of the door or window.

The primary object of the invention is the provision of a simple and compactly arranged, portable device that may be used by 20 travellers or others for securing a door or window, and which, while comparatively inexpensive in cost of production is simple in construction and operation, reliable, and a comparatively perfect mechanism for performing its required functions.

The subject matter of the invention involves the utilization of a door securing device of that type in which a hammer is released to explode a detonating cap or cartridge, upon the attempt to open the door or window with which the device is used, and even after the detonation or alarm, the door is held in fastened position except against 30 breaking down thereof.

The invention consists in certain novel combinations and arrangements of parts as will be hereinafter more fully described and claimed.

In the accompanying drawings I have 40 illustrated one complete example of the physical embodiment of my invention as now in actual use, in which the parts are combined and arranged according to the best mode I have thus far devised for the practical application of the principles of my invention.

Figure 1 is a perspective view of a device embodying the novel features of my invention, the parts being shown in inoperative 50 or "day-time" position.

Figure 2 is a plan view of the device in open position, as in Figure 1, with the slidable, dispensable cover or lid removed therefrom to expose the interior construction of the device.

Figure 3 is a vertical, sectional, longitudinal view at line 3—3 of Figure 4 with the parts open and inoperative.

Figure 4 is a transverse sectional view at line 4—4 of Figure 3, with the hammer blade 60 in firing position.

Figure 5 is a top plan view of the device in operative position showing its relation to the door, door jamb and door frame.

In the preferred form of the invention as 65 illustrated in the drawings, in Figure 5 I have shown the device in its relation to the usual hinged door 1, door frame 2, and door jamb 3, the door being fastened or secured by the device embodying the invention which 70 is secured to the door frame, and the carrier-bolt of the fastening device is holding the door against the jamb 3 to prevent opening of the door.

The portable fastening device is compact 75 in form and sufficiently small in size to be carried about the person, and comprises a metallic locking plate or fastening blade 4 having a pair of spurs or teeth 5 adapted to be forced into the material of the door 80 frame, and a shoulder 6 on the plate adjacent these spurs is adapted to bear against the edge of the door frame, thus anchoring the blade or plate and its connected device firmly and securely to the door frame.

A carrier-bolt or hollow block 7 is hinged at one end of the fastening plate, by a strong hinge joint 8, and this carrier bolt, which is of comparatively heavy weight and strength of material for performing its required functions is fashioned with side walls 9, 9, projecting from the body of the bolt. These walls are provided with complementary slots 10, 10, similar to open bayonet-slots near one end of the bolt, and 90 near the other end thereof a pair of laterally extending exterior pins 11 are provided.

In connection with the carrier bolt I utilize a slidable, dispensable, cover plate 12, for releasing a detonating device, the plate 100 being slidable relative to the carrier bolt and provided with open slots 13 in integral side lugs projecting therefrom and axially aligned pins 14 projecting to the interior thereof from the side flanges 14'. The slotted flanges 13 and the flanges 14' are spaced apart, in pairs, to act as guides and slip over the free edges of the walls of the carrier block, and the co-acting pins and slots on the block or bolt and cover lid, permit a 110

limited sliding movement of the cover lid on the bolt, which when the cover lid is released as will be described, will terminate in a casting-off or snapping-off movement of the lid with relation to the carrier bolt.

Within the side walls of the carrier-bolt is provided a reversible, spring pressed, hammer blade 15, made up of suitable metal, with its tip end 15' projecting slightly beyond the carrier-bolt which is notched at 7' for insertion of the finger nail, or a tool to swing the hammer blade to operative position on its pivot bar. The hammer-blade has a detonating head 16 and is pivoted on the transversely extending bar 17 fixed in the side walls of the carrier bolt, while a spring 18 coiled about the bar has one end 19 bearing on the top face of the blade and its opposed end 20 bearing on the face of the carrier bolt, as shown in Figure 2. In this manner the blade is held down flat as seen in full lines Figure 2, or when swung over to dotted position in said figure, and the slide cover plate released, the coiled spring will violently throw over the hammer blade to detonate a cap or cartridge retained on the anvil 21.

The dispensable cover plate is attached to the carrier bolt by means of a chain 22 in order that it may not be misplaced or lost when thrown from the bolt under action.

In "loading" the device and preparing it for use, the hammer-blade, after the cover-plate has been removed, is swung over or reversed on its pivot against the tension of the spring 8 to dotted position in Figures 2 and 3. The blade is held in this position while the cover-plate, grasped in the right hand, is applied to the carrier-bolt and the pins 14 of the cover-plate are inserted in the open bayonet slots 10 of the carrier-bolt. The slotted end of the cover-plate is now brought down over and parallel with the carrier-bolt so that the open slots 13 of the cover-plate will slide over the pins 11 of the bolt, as the cover-plate is moved to the right (see Figure 1). By moving the cover plate to dotted position of Figure 3 the plate is "set" or "cocked" for firing, and in this position one end of the plate projects (as indicated in Figures 3 and 5) beyond the end of the carrier bolt. The carrier bolt is now ready to be turned on its hinge 8 and folded over to dotted position of Figure 3, and the blade 4 is applied to the door frame 2 as in Figure 5, the door is closed, and the carrier bolt is turned to closed or folded position, as in Figure 5. If pressure is applied to the door from the exterior, the force exerted will result in sliding the cover plate its projected

distance on the bolt, and this movement is sufficient to free the cover plate of its pin and slot connections. This movement frees the cover plate and releases the tension of the spring 18, whereupon the hammer blade, under spring pressure is swung on its pivot, throwing off the cover-plate and causing the hammer blade to strike the cap or cartridge to detonate the latter, thus providing an audible alarm. The cover-plate is retained by its chain ready for re-setting. The carrier-bolt, however, remains in fastened position, and although the door may be moved slightly, the pressure of the door on the bolt serves only to more securely hold the door by the resistance of the bolt, as the pressure thereon is sustained by the hinge joint, and the pull on the fastening blade 4, which has its teeth embedded in the door frame, is not sufficient to release the blade from the door frame, under ordinary conditions.

In Figure 1 the cover plate is shown in safety position with the small slots 23 of the flanges 13 engaging pins 24 on the exterior of the carrier-bolt, and while in this position the device may be retained for use when required, and after application to the door frame, the cover plate may be slid from safety to cocked position without disengagement from the carrier bolt.

What I claim as new and desire to secure by Letters Patent is—

1. The combination with a fastening plate of a hollow hinged, carrier-bolt, a reversible, spring pressed hammer-blade pivoted in the carrier bolt, and a slideable and dispensable releasing cover-plate on said carrier bolt actuated by pressure thereon, for the purpose described.

2. The combination with a fastening plate, of a hollow, hinged, carrier bolt, a reversible spring pressed hammer-blade pivoted in the carrier bolt, a slideable, dispensable releasing cover-plate on said carrier bolt, actuated as described, and means on the bolt and cover-plate co-acting to hold the latter in safety position.

3. The combination with a fastening plate, of a hollow, hinged carrier-bolt having complementary slots in its side walls, and complementary lateral pins at its opposite end, of a reversible, spring pressed hammer-blade pivoted in the carrier-bolt, and a slideable, dispensable releasing cover-plate having pins and slots complementary to the slots and pins of the carrier-bolt, for the purpose described.

In testimony whereof I affix my signature.

ARTHUR A. KELLEY.
